UNITED STATES PATENT OFFICE.

FREDERIC WILLIAM HOGG, OF THE DALLES, OREGON.

PNEUMATICALLY-OPERATED WINDOW-CLEANER.

1,144,203.

Specification of Letters Patent. Patented June 22, 1915.

Application filed July 14, 1914. Serial No. 850,920.

To all whom it may concern:

Be it known that I, FREDERIC WILLIAM Hogg, a citizen of the United States, residing at The Dalles, in the county of Wasco and State of Oregon, have invented certain new and useful Improvements in Pneumatically-Operated Window-Cleaners; and I do hereby declare the following to be a full, clear, and exact description of the invention, such as will enable others skilled in the art to which it appertains to make and use the same.

This invention relates to pneumatically operated window cleaners, designed for use in cleaning the windows in front of the motorman on a street car, and one of the principal objects of the invention is to provide a device for wiping off rain or snow from a window through which the motorman might look to see if the track is clear, and means whereby the window cleaner may be operated through connections from the air brake system of the car.

Another object of the invention is to provide a window cleaner adapted to be operated by means of a cylinder and piston operatively connected to an air tank or through an air brake system of a car, and to provide means whereby the reciprocation of the piston carries a window cleaner across the window pane from top to bottom for wiping rain or snow off the window, whenever required.

These and other objects may be attained by means of the construction illustrated in the accompanying drawings, in which—

Figure 1 is a front elevation of a motor car showing a pneumatically operated window cleaner mounted thereon and made in accordance with this invention; Fig. 2 is a vertical sectional view through the cylinder and the guide tube for the cleaner, Fig. 3 is an enlarged sectional view taken on the line 3—3 of Fig. 2, and looking in the direction indicated by the arrow, Fig. 4 is a front elevation of the pneumatically operated window cleaner removed from the car, Fig. 5 is a sectional view and showing the manner of making the connections at the top and bottom of the cylinder, said connections leading to a lever to be operated by the motorman for moving the window cleaner up or down, and Fig. 6 is a sectional view taken on the line 6—6 of Fig. 4, looking in the direction indicated by the arrow.

Referring to the drawings, the numeral 1

designates the front of an ordinary motor car and 2 is the front window through which the motorman usually looks to see if the track is clear.

Secured preferably to the outer side of the car parallel with the window is a cylinder 3, and mounted in the cylinder is a piston rod 4 carrying a piston head 5. The piston rod 4 is provided with an angular member 6 at its lower end, and connected to or formed integral with the said angular member is a vertical rod 7 mounted in a guide tube 8 secured to the front of the car at the side of the cylinder 3. The guide tube 8 is provided with a long vertical slot 9, and connected to the upper end of the rod 7 is a window cleaner, comprising a tube 10 having a longitudinal slot therein, and connected to the tube 10 is a rubber window cleaner or wiper 12, preferably connected to the tube 10 by a metal cap 11, as shown more clearly in Fig. 3. However, other forms of window cleaners or wipers may be utilized.

Communicating with the cylinder 3 near its upper end is a pipe 13 having a vertical branch 14, which connects with the pipe 15 leading to the air brake system, and a two-way valve 16 is provided with a stem 17 which can be operated to admit air through the pipe 14 and 13 into the cylinder 3, or which can be operated to admit air through the pipe 18 into the cylinder 3 near the bottom thereof. The pipes 13 and 18 extend through the front of the car, as shown more clearly in Fig. 5.

The operation of the invention may be briefly described as follows: When the lever or stem 17 of the valve 16 is operated air is admitted through the vertical pipe 14 and through the pipe 13 into the cylinder 3 near the top thereof to force the piston head 5 downward and to thus carry the rod 7 downward and with it the window cleaner 10 which is in contact with the window pane at the front of the car.

For guiding the window cleaner 10 in its vertical movement, guide bars *a* may be connected to the opposite sides of the window pane, and the ends of the cleaner may be guided by these bars in any suitable manner.

It will be apparent from the foregoing that the invention is simple in construction, can be quickly applied to the front of the car, is efficient in operation, and inexpensive to manufacture. While the device has been

described in connection with a car window, it will be obvious that it may be used for cleaning windows in dwellings or apartment houses without material change in the structure.

Various changes may be made in the details of construction without departing from the spirit and scope of the invention as defined in the claims.

10 What is claimed is:—

1. A window cleaner comprising a cylinder, a piston in said cylinder, a piston rod connected to said piston and provided with an angular arm, a rod connected to said arm, a guide tube in which said rod is mounted, a window cleaner connected to said rod, and means for moving the piston up or down in the cylinder.
2. A pneumatically operated street car window cleaner, comprising a cylinder communicating with the source of compressed air, a piston in said cylinder, a piston rod extending through the bottom of the cylinder, an arm connected to said piston rod, a rod connected to said arm, a guide tube in which said rod is mounted to reciprocate simultaneously with the piston, said tube having a longitudinal slot therein, a window cleaner connected to said rod.
3. A pneumatically operated window cleaner for street car windows, comprising a cylinder, a piston mounted in said cylinder, a piston rod, an arm carried by the piston

rod, a rod carried by the arm, a slotted guide tube, in which said rod is mounted, a window cleaner connected to said rod, guides for said window cleaner, and means for admitting compressed air near the opposite ends of said cylinder for reciprocating said plunger.

4. In a pneumatically operated window cleaner for street car windows, the combination of a cylinder communicating with the air brake system of the car, a piston in said cylinder, a window cleaner, guides for said window cleaner, and connections between the said piston and said cleaner to move the cleaner simultaneously with the piston for cleaning a window.

5. A pneumatically operated window cleaner comprising a cylinder, a piston rod, a piston in said cylinder, an arm connected to the piston rod and provided with a supporting rod disposed parallel to the piston rod, a slotted guide tube, a window cleaner connected to said supporting rod, said window cleaner comprising a tube having a slot therein, a rubber wiper connected to said tube, and guide bars at opposite sides of the window for said window cleaner.

In testimony whereof I affix my signature in presence of two witnesses.

FREDERIC WILLIAM HOGG.
